UNITED STATES PATENT OFFICE.

ENOCH M. CRUMPTON, OF BRYSON, TEXAS.

INCUBATOR.

1,284,611.

Specification of Letters Patent. Patented Nov. 12, 1918.

Application filed March 13, 1918. Serial No. 222,209.

To all whom it may concern:

Be it known that I, ENOCH M. CRUMPTON, a citizen of the United States, residing at Bryson, in the county of Jack and State of Texas, have invented certain new and useful Improvements in Incubators; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to new and useful improvements in incubators and comprises a chamber with shafts journaled in the walls thereof, and in the provision of egg trays made up of two complementary parts hinged together, and having partitions which are held together when the sections are closed to receive the shafts with which the trays rotate.

25 The present invention is clearly illustrated in the accompanying drawings, which, with the letters of reference marked thereon, form a part of this application and in which drawings similar letters of reference indicate like parts throughout the several

30 views in which,

Figure is a side elevation of the invention.

Fig. 2 is a central vertical sectional view through the incubator.

35 Fig. 3 is a sectional view taken on line 3, 3 of Fig. 1, and Fig. 4 is a side elevation of the side at right angles to the showing in Fig. 1.

Reference now being had to the details of the drawings by letter A designates the 40 casing of the incubator which may be made of any suitable material, and B designates legs of the apparatus. The incubator has an inner wall A' spaced apart from the outer wall, leaving a hot air space between the walls. A suitable lamp C supported upon the table B³ upon the cleats B², has a burner C² and a chimney C' with vent holes C' therein. The upper portion of the chimney passes through a hole in the bottom of the casing and forms means for directing the heat from the lamp to the heating tank D from which pipes D' lead in four directions to the spaces between the two walls. The inner wall A' has apertures 45 for the reception of the perforated ends D³

of the pipes D² which communicate with the pipes D'.

Said tank D has a pipe D⁴ leading from its top centrally and which extends through an opening in the bottom of the incubator chamber, and has fitted thereto a cap D⁵.

The incubator is provided with a suitable hinged top E with glass panels E², and egg trap made up of sections G and G' are hinged together at G², and their free edges have fastening latches G³. Within the egg trays are partitions forming cells H to contain the eggs. The trays are fixed to the shafts F, which are journaled in the opposite walls of the incubator as at F'. To the corresponding ends of the shafts are secured the bevel gear wheels F², each in mesh with a beveled pinion F³ keyed to a shaft F⁴ journaled in bearings K' F'. A gear wheel K³ is keyed to the shaft F⁴ and K² is a 75 crank handle also fastened to the end of the shaft F⁴ for operating same when the apparatus is to be actuated by manual power. Journaled in the bracket K, is a shaft K⁴ to which a gear wheel K⁵ is splined as at 80 K⁶, and K⁷ is a set screw engaging a threaded hole in the hub of the gear wheel K⁵, and forms means whereby the wheel K⁵ may be held in different adjusted positions accordingly as it may be desired to cause 85 wheels K⁸ and K⁹ to turn together, when the apparatus is adjusted to operate automatically. A suitable clock work mechanism is mounted in the casing M supported on the bracket M' and M² is a gear wheel actuated by the clock work, and which, when the gear wheel K⁵ is at its farthest limit toward the incubator casing, is in mesh with the wheel K⁹. In this adjusted arrangement, the trays may be given 90 a revolution at any predetermined moment through the medium of the clock work.

In operation the eggs are placed within the cells of the trays and fitted therein so that when the trays are rotated, the eggs 100 will not be jarred by the rotary movements of the trays. Heat at the desired temperature for proper incubation of the eggs is furnished from the lamp, and a sufficient quantity of moisture is introduced into the 105 interior thereof through the pipes D², and which moisture will tend to moisten and soften the egg shells to the right consistency. When it is desired to have the trays rotated automatically through the medium of the 110

clock work mechanism, the gearing is adjusted as shown in Fig. 1. When it is desired to operate the trays manually, the wheels M^2 and K^6 are thrown out of gear 5 and the shaft F^4 may be rotated through the medium of the handle K^2 .

What I claim to be new is,—

In an incubator chamber, a shaft journaled in the opposite walls thereof having 10 a portion angular in cross section, an egg tray made up of two complemental parts hinged together and provided with parti-

tions, the adjacent ends of which are adapted to be held together when the sections are closed, the partitions in central sections 15 thereof having angular outlined recesses to receive the angular portion of the shaft, and means for rotating the shaft.

In testimony whereof I hereunto affix my signature in presence of two witnesses.

ENOCH M. CRUMPTON.
